SERUM SEPARATION APPARATUS
AND METHOD

Andrew F. Farr, South Gate, Calif., assignor to Bio-consultants, Inc., Glendale, Calif., a corporation of California

Filed July 6, 1964, Ser. No. 380,497
8 Claims. (Cl. 233—26)

This invention relates to the method and apparatus for separation of serum from dispersed solids, particularly blood serum from suspended cells, for the purpose of obtaining samples of clear serum.

One object of the invention is to provide a method for easy separation of a liquid from suspended solids. Another object is to provide means for easily and quickly separating blood serum from the cellular bodies which have been settled to the bottom portion of a tube, for example as by centrifuging. A further object is to provide inexpensive and disposable apparatus for the removal and storage of the serum from a centrifuged tube of blood. Another object is to provide means for accurately separating one immiscible liquid from another, in a tubular container.

These and other objects are attained by my invention which will be understood from the following description, reference being made to the accompanying drawings in which—

FIG. 1 is a side elevational view of an assembled serum separation apparatus;

FIG. 2 is a cross-sectional view taken on the line 2—2 of FIG. 1;

FIG. 3 is a side elevational view of the same in disassembly with parts broken away and shown in section;

FIG. 4 is a diagrammatic representation of the apparatus in use showing the delivery of serum to the upper chamber of the apparatus for temporary storage therein;

FIG. 5 is a diagrammatic representation of the apparatus in use showing delivery of serum to another vessel; and

FIG. 6 is a side elevational view of an alternative arrangement with a shortened capillary tube discharging within the plunger tube.

In the examination of blood samples in a clinical laboratory, it is frequently necessary to examine the blood serum after separation from the suspended cellular material, and for this purpose it is customary to subject the tubes in which the blood samples are delivered to the laboratory, to centrifugal force to cause the settling of the cells to the bottom of the tube. In certain clinical laboratories, hundreds of tube samples of blood are handled per day, and it is important to conserve time and provide completely accurate identification (by attached labels) of each sample both before and after separation of the serum from the solids.

In FIG. 1 there is shown an assembled separation apparatus consisting of an outer tubular member 11, which is generally a sample tube in which the blood sample has been delivered to the laboratory, and in which the blood may be subjected to centrifuging to settle out the cells. A plunger tube 12 having a soft rubber piston head 13 attached to its inner end is arranged to be moved longitudinally within and slidingly fitting the inside wall of the member 11, the plunger tube 12 being considerably longer than the tube 11 to provide handle means. The outer end 14 of the plunger tube 12 is open, and there is provided within said tube a plastic flexible small bore or capillary tube 15, whose lower end 16 extends through an opening 17 provided in the piston head 13, and whose opposite outer end 18 may extend beyond the open end 14 of the plunger tube 12, although it may terminate within the

2

plunger tube if desired. The outer end portion 18 of the flexible tube 15 may be doubled back into the plunger tube 12 (as shown in FIG. 4) or it may be free to communicate with another receiving vessel 19.

The method of separating the serum from the suspended solids starts with the centrifuging of the blood sample in the tube 11, following the well known test procedure. After centrifuging, the plunger tube 12 with piston head 13 is inserted in tube 11, the capillary tube 15 being in place with its lower end attached to and penetrating the piston head 13 so that its lower end communicates with the gas or liquid contents of the tube 11 below the piston head 13. As the head 13 is pressed into the tube 11, the air above the serum 20 is released to the atmosphere, and when the end of the capillary tube which extends through the piston head 13 makes contact with the serum 20, the serum passes out through the capillary tube 15, without disturbing the settled out solids or cellular bodies 21. If the outer end 18 of the capillary tube is doubled back to reenter the plunger tube 12, as shown in FIG. 4, the separated serum is collected and retained above the piston head 13 in the plunger tube 12, where it may be kept until required for further examination. Alternatively, as shown in FIG. 5, the outer end 18 of the capillary tube 15 may be extended outside the plunger tube 12, to deliver serum to any desired receiving vessel 19. A portion of serum may be placed in the receiving vessel 19, or several such vessels, and then the remainder of the separated serum may be collected and retained in the plunger tube 12, by doubling back the outer end 18 of the capillary tube 15 into the plunger tube. The piston head 13 may be pressed down until all of the separated serum 20 above the settled out solids 21 has been removed. The portion of the serum which surrounds the cells or solid particles is not removed. Because of the extension of the capillary tube 15 outside the plunger tube 12, the serum in said plunger tube 12 may not return to the tube 11.

In an alternative arrangement, the capillary tube 15A may terminate inside the plunger tube 12 as shown in FIG. 6, in which arrangement the separated serum is collected in the plunger tube 12, from which it may be removed by pouring or in any other convenient manner.

After the separation has been completed, and the retained separated serum is no longer needed, the plunger tube 12, with piston head 13 and capillary tube 15 may be removed and discarded. The tube 11 is generally cleansed and re-used for new blood samples, but if desired, the entire apparatus may be discarded, since the apparatus is very inexpensive, whether made of glass or of synthetic plastic, thus avoiding washing and re-sterilizing.

While the use of the apparatus has been described with reference to the separation and collection of blood serum, the apparatus has other uses. For example, it may be advantageously used to remove a separated top layer in a tube containing immiscible liquids, as sometimes used in liquid extractions, particularly for analytical purposes. It may also be used for removing relatively large amounts of liquid from a settled small body of an analytical precipitate in a tube, in completing well known analytical procedures.

Where the descriptive word "capillary" is used herein it refers to small-bore plastic tubing having a bore of about $1/32$ inch.

The advantages of the method and use of the apparatus will be apparent from the above description. The saving in handling time for making the separation, and the avoidance of re-labeling of the temporarily stored serum (avoiding the danger of mislabeling) make the invention useful in analytical examinations.

The objectives stated in the beginning have been attained.

I claim:

1. An apparatus for separating a clear liquid from settled-out immiscible liquids and/or settled-out solids in a suspending liquid contained therein, comprising an outer transparent tubular member; a plunger tube longitudinally movable within said outer member; a piston head mounted on the closed inner end of said plunger tube, said piston head making sliding sealing contact with the inner walls of said outer tubular member, and flexible capillary tube disposed within said plunger tube, one end of said capillary tube extending through said piston head to communicate with the space in said outer tubular member below said piston head.

2. An apparatus for separating a clear liquid from settled-out immiscible liquids and/or settled-out solids in a suspending liquid contained therein, comprising an outer transparent tubular member; a plunger tube longitudinally movable within said outer member; a piston head mounted on the closed inner end of said plunger tube, said piston head making sliding sealing contact with the inner walls of said outer tubular member, and flexible capillary tube disposed within said plunger tube, one end of said capillary tube extending through said piston head to communicate with the space in said outer tubular member below said piston head, said flexible capillary tube extending out of the opposite open end of said plunger tube.

3. The apparatus defined in claim 2 in which the outer end of the capillary tube is doubled back so that it communicates with said plunger tube.

4. In an apparatus for separating a clear liquid from separated out solids, contained in a centrifuge tube, a plunger tube longitudinally movable within said centrifuge tube; a piston head mounted on the inner end of said plunger tube, said piston head making sliding sealing contact with the inner walls of said outer tubular member, and a flexible capillary tube disposed within said plunger tube, one end of said capillary tube extending through said piston head to communicate with the space in said tubular member below said piston head.

5. In the plunger tube defined in claim 4, a flexible

capillary tube which extends beyond the outer end of said plunger tube.

6. In the plunger tube defined in claim 4, a flexible capillary tube which terminates inside said plunger tube.

7. The method of removing a separated lighter liquid from a heavier material contained in the bottom portion of a first zone comprising:

(a) Applying mechanical pressure by pushing tubular plunger means against the surface of the overlaying liquid whereby the end portion means of said plunger means decreases the volume of said bottom portion of said first zone;

(b) Relieving said pressure by displacing said lighter liquid from substantially the surface portion thereof through orifice means in said end portion of said plunger means;

(c) Moving said displaced liquid from said surface through conduit means disposed internally of said plunger means and distinct from the tubular wall of said plunger means to a point displaced from said surface contacted by said plunger means;

(d) Then flowing said moved liquid into a second zone.

8. The method of claim 7 wherein the second zone is within the bottom portion of said tubular plunger means.
